UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

CANOPY-FIXTURE.

1,280,826.

Specification of Letters Patent.

Patented Oct. 8, 1918.

Application filed July 24, 1913. Serial No. 780,987.

To all whom it may concern:

Be it known that I, HENRY T. PAISTE, a citizen of the United States, residing in Philadelphia, Pennsylvania, have invented 5 certain Improvements in Canopy-Fixtures, of which the following is a specification.

One object of my invention is to provide a relatively simple fixture which may be easily applied to the ordinary form of electric 10 wall bracket and which shall be designed to receive a contact or attachment plug of suitable construction.

I also desire to provide a fixture which under conditions of use shall be partially 15 concealed or covered by the canopy of a wall or other bracket or fixture with which it is associated, and which in addition to possessing but a few inexpensive parts, shall be substantial as well as ornamental in appearance.

20 These objects and other advantageous ends I secure as hereinafter set forth, reference being had to the accompanying drawings, in which:

Figure 1 is a side elevation of a lamp 25 bracket showing my invention as applied thereto;

Fig. 2 is a front elevation of the bracket shown in Fig. 1;

Fig. 3 is a front elevation of the receptacle 30 structure and its associated parts constituting a portion of my invention; and

Figs. 4 and 5 are respectively sections on the lines *a—a* and *b—b*, Fig. 3.

In the above drawings 1 represents the tubular body of a gas-electric bracket having a gas burner 2 and a lamp socket 3, in the latter of which is mounted an incandescent lamp 4. Interposed between the tubular body 1 and the wall or other structure on 40 which this bracket is supported, is a canopy 5 which receives and conceals the gas and electric connections, this canopy being usually formed of relatively thin spun or pressed metal. In the present case the lower portion 45 of the canopy is provided with a substantially rectangular recess adjacent its edge to permit of the passage of the base or main portion of the fixed structure shown in detail in Figs. 3 to 5 inclusive. This structure 50 may be described as consisting of a substantially cylindrical body portion 7 having in the present instance an ornamental inclosing casing 8 of metal connected by a neck portion 9 of substantially rectangular section 55 with a somewhat extended flat head piece 10.

As shown in Fig. 5, the cylindrical body 7 is hollow, having in its outer face a rectangular opening 11 and containing a pair of oppositely placed spring contacts 12 and 13. These latter are preferably both of the same 60 construction and each consists of an elongated resilient strip of metal having one end perforated and bent at right angles and the opposite end bent through an angle somewhat less than 180 degrees. Each of said 65 contact pieces is held within the canopy of the body 7 by a screw or bolt 14 whose head is counter-sunk in the bottom face of the insulating structure, while its opposite end is threaded for the reception of a nut whereby 70 said contact strip is clamped in place.

The two nuts of these screws or bolts are 75 preferably separated from each other by a rib 15 integral with the body structure 7, so that their accidental short circuiting is effectually prevented. Each of the counter-sunk cavities or recesses for the heads of the screws 14 communicates directly with a channel 16 formed in the underface of the fixture structure and extending through the neck 9 80 into the head 10 where it communicates with a hole or passage 17 extending from the back to the face of said head. The latter is also provided with two counter-sunk holes 18 85 designed for the reception of screws whereby the fixture as a whole may be rigidly fixed to the supporting structure on which it, with the canopy fixture, is to be mounted.

In mounting the apparatus above described, the lamp bracket is first connected to 90 a supporting fixture, a gas pipe or the like in the well known manner, the canopy 5 being loose and freely movable on the tubular or other supporting member. The fixture 6 is then mounted on a supporting structure 95 in such a position that when the canopy 5 is finally put in place, the neck 9 will extend through and fill the rectangular recess of the bottom edge of the said canopy, while the head 10 will be within the canopy and the 100 body 7 outside of but immediately adjacent the same, the whole being held in place by screws passed through the openings 18. Two insulated conductors 19 and 20, electrically connected to the main supply conductors 21 105 and 22, respectively extend into the openings 17 and through the channels 16, at the extremities of each of their ends are respectively connected to or electrically engaged with the screws or bolts 14. Thereafter a 110

contact or attachment plug such as that shown and described in my application for Patent 780,986, filed July 24, 1913, may be inserted through the opening 11, with its side contacts in engagement with the turned over resilient ends of the spring contact members 12 and 13, so that current is supplied to the circuit of which said side members are the terminals.

10 From the above it will be appreciated that the device constituting my invention is not only relatively simple and easily applied to existing electric lamp brackets but that it is ornamental in appearance and 15 highly convenient.

While I preferably employ a receptacle or attachment plug which as shown in Fig. 5, is provided merely with two similar spring contacts for engagement with the 20 side contacts of a contact plug, I may without departing from my invention, use other forms of receptacles or sockets as may be found advisable under varying conditions.

I claim:

25 1. The combination of a canopy having electrical conductors therein; a receptacle having a lateral extension projecting into said canopy and provided with contacts; and electrical conductors connecting the contacts of the receptacle to the conductors in the canopy.

2. The combination of a canopy having an opening adjacent one edge; a receptacle having a laterally projecting base structure extending through said opening into the 35 canopy; with conductors connected to the contacts of the receptacle and extending through the base structure of the canopy.

3. As a new article of manufacture, a receptacle consisting of a body portion, a 40 laterally projecting neck and a head both integral with said body, there being a cavity in the body and channels in the neck and head for electrical conductors; contacts permanently mounted in the cavity of the 45 body; with a canopy covering said head.

4. The combination of a receptacle having a body, a head, and a laterally projecting neck connecting the head and the body; contacts for the receptacle; with a canopy 50 closing the head and having an opening for the reception of the neck, there being channels for electrical conductors leading from the terminals of the contacts, through the neck and into the head.

In testimony whereof, I have signed my name to this specification, in the presence of two subscribing witnesses.

HENRY T. PAISTE.
